Primary Examiner — Natasha Vujcic*Assistant Examiner* — Gilbert B Ford(74) *Attorney, Agent, or Firm* — Mark M. Friedman(57) **CLAIM**

The ornamental design for an orthopedic thumb splint, as shown and described.

DESCRIPTION

FIG. 1 is a top view of an orthopedic thumb splint showing my new design;

FIG. 2 is a bottom view thereof;

FIG. 3 is a front perspective view thereof;

FIG. 4 is an exploded front perspective view thereof; and, FIG. 5 is another perspective view thereof shown in a position of use.

The broken lines in the drawings illustrate portions of orthopedic thumb splint and portions of the environment that form no part of the claimed design.

1 Claim, 5 Drawing Sheets(56)
